JOHN W. SMITH, OF PHILADELPHIA, PENNSYLVANIA, ASSIGNOR TO BUDD WHEEL COMPANY, OF PHILADELPHIA, PENNSYLVANIA, A CORPORATION OF PENNSYLVANIA.

MACHINE FOR ROLLING DISKS.

Application filed October 5, 1920. Serial No. 414,848.

My invention relates to machines for rolling disks, and more especially to the rolling of disks of tapered cross-section. In accordance with my invention, a disk of such cross-section may be rolled from a blank initially of uniform thickness without causing buckling or other injurious deformation; and the operations can be carried on expeditiously and, to a large extent, automatically. Various other advantages obtainable through my invention will appear from the description hereinafter of the best embodiment at present known to me; its scope and essentials, in its various phases and aspects, will be indicated in my claims.

In the accompanying drawings, Fig. I is a front elevation of a machine embodying my invention.

Fig. II is an end elevation of the same viewed from the right of Fig. I.

Fig. III is a central vertical section of the machine.

Fig. IV is an enlarged fragmentary sectional elevation, showing the cooperative elements by which the rolling is accomplished.

Fig. V is a sectional view of a valve by which certain operations of the machine are controlled.

Figs. VI and VII are respectively a plan and a cross-sectional view of a sheet metal blank as it appears before the rolling operation.

Fig. VIII is a detail view, partly in cross-section, showing the relative positions of the rolling elements and the blank operated upon during the rolling process, and

Fig. IX is a cross-sectional view of the finished product.

The structure herein shown comprises a circular table 1 which serves as a support for the blanks which are to be rolled, and a pair of cooperating conical rolls 2-2', having a comparatively narrow cylindrical tread and adapted to be moved radially outward from the center of the table 1 in opposite directions while in pressure contact with the blank.

The necessary pressure of these cooperating elements on the blank is maintained during the rolling operation by suitable mechanism which will be later described. The support and rolls 2 are bodily rotatable rel-

ative to one another, and also movable toward and away from one another.

The table 1 has a removable top or die plate 3 which is of arched cross-sectional configuration, as clearly shown in Figs. III and IV. The upper surface of the element 3 is conically concave, and hence slopes downward from its periphery toward its axis as indicated at 4. This slope determines the degree of attenuation in and the taper of the finished disk, as is explained hereinafter. The removable die plate 3 rests upon a rotatable support 5, and is held in proper axial alignment therewith by engagement of the shoulders 6 of its central bottom recess with an annular ridge 7 on the support; it is secured in place by bolts 8. At its centre, the die plate 3, has an upwardly tapered stud 9 adapted to fit a central orifice in the blank and positively center and hold the latter from displacement during the rolling operation. The supporting member 5 is sustained by a roller bearing 10 housed in a central recess 11, of the base 12 of the machine, said recess being in practice filled with grease to provide for the proper lubrication of the bearing. An annular apron 13, tends to prevent escape of the lubricant from the recess 11, and an annular guard 14 surrounding the table structure intercepts any leakage which may be thrown off during rotation of the table.

The integral depending tubular shank 15 of the support 5 is journaled for rotation in a sleeve bearing 16 suitably set within the base 12, and has attached to its lower end an actuating bevel gear 17. This gear meshes with a pinion 18 secured upon a horizontal drive shaft 19 journaled in a removable bearing frame 20, which is mounted within an appropriate opening in the base 12. The gears 17 and 18 run in a grease filled inner chamber 21 of the base, which chamber is closed at its bottom by a diaphragm 22. The protruding end of the drive shaft 19 is tapered and threaded as at 23 for the attachment of any suitable means (not shown) whereby it may be operatively connected to a convenient source of power.

For the purpose of cooling the supporting table 1 when the machine is used for rolling preheated blanks, I have provided a water

circulating system. This system comprises a pipe 24 extending axially through the tubular shank 15 of the support 5 and discharging into the hollow of the die plate 3. 5 A stationary cross piece 25 attached to the upper end of the pipe within the hollow of the die plate tends to prevent swirling of the cooling medium during rotation of the table. The discharge drains downward through the 10 duct of the shank 15 around the pipe 24 into a chambered fitting 26 secured to the diaphragm 22 previously referred to, and is finally carried off through a pipe 27. A tubular extension piece 28 forming a prolongation of the axial duct in the shank 15 runs within a stuffing box 29. This construction, it will readily be seen, affords a seal between the grease chamber 21, and the water circulatory system. 15

20 Rising from the base 12 are upright columns or shafts 30—30 and 31—31 which are united at their upper ends in pairs by bridging cross pieces 32—32. A frame 33 with guide sleeves 34 embracing the columns 30—30 and 31—31 is adapted to slide vertically under guidance of the columns. Downward movement of the frame 33 is limited by the engagement of cylindrical extensions 35 of its guide sleeves 34 with adjustable collars 36 set upon the threaded portions 37 of the columns, and the upward movement of said frame is similarly limited by adjustable stop collars 38. The adjustment of the collars 36 adapts the machine to operating 25 upon blanks of different initial thickness. The rolls 2—2 already referred to are journaled in carriages 40—40 which are mounted for horizontal sliding movement in a common guideway 41, formed in the lower part of the slide frame 33. From Fig. II, it will be seen that the centre of the carriage guideway 41 intersects the axis of rotation of the turn table 1, so that, in being shifted outward in opposite directions under guidance 30 of the slideway, the rolls are moved radially cross-wise of the top of the turn table, as previously mentioned. Each of the rolls 2 (see Fig. IV) is fixed upon a shaft 42 which is journaled in roller bearings 43 and 44 housed in appropriate cavities of the integral bracket arms of the carriage 40. In addition to the bearings 43 and 44, double ball bearings 45 are provided for resisting the outward thrust of the rolls 2, 2. The cavities 35 for the several bearings are kept filled with grease for lubricating purposes, in a manner already well understood.

In order to provide for carrying off heat from the rolls 2, 2 each of said rolls is made hollow, as best shown in Fig. IV so that water or other cooling medium may be circulated therethrough. The cooling medium is conducted to each roll through a tube 46 axially disposed within the bore of the corresponding shaft 42. This tube 46 extends 40 inward to a point adjacent the inner end of the shaft, and the bore of the latter is there closed by a removable cap piece 47 (with a clean-out plug screwed therein), the joint being sealed by an appropriate gasket or washer 48. After issuing from the inner end of the tube 46, the cooling medium flows outward about said tube in the portion 49 of the shaft bore, as far as permitted by the internal ridge 50; and then enters the cavity 55 of the roll through a lateral duct 51. The exit from said cavity is through a second duct 52, preferably opposite the first mentioned duct, and the fluid next enters the portion 53 of the shaft bore, which, in turn, 45 discharges through orifices in a retaining collar 54 into a collecting chamber in an extension 55 of the roll carriage 40. The drainage from the extension 55 may be conducted to any convenient point for disposal through a pipe shown at 56. The supply of the cooling medium may be delivered, for example, by a flexible conduit (not shown) attachable to a nipple 57 set into a projecting boss 58 on the extension 55,—this nipple communicating with the protruding end of the tube 46, which at this point lies in a stuffing box. 50

In order that the shifting of the rolls in opposite directions may be effected gradually and uniformly, they are shifted by common actuating means including a pair of rockers 65—65 fulcrumed on the frame 33 at 66—66 and connected by adjustable links 67—67 to the roll carriages 40—40, and by toggle links 68—68 to the lower end of a movable hydraulic cylinder 70. The piston 71 of the cylinder 70 is supported by a superstructure 72 mounted upon a central boss on the frame 33. The piston 71, is of differential double-acting type, and has a head adapted to be acted upon by a suitable pressure medium both above and beneath. A continuous supply of pressure fluid is conducted through a pipe 74 and port 75 to the space 76 above the piston head; this tends to keep the cylinder 70 raised and the rolls 2—2 in their innermost or starting position. When the rolls are to be gradually separated during the rolling operation, fluid under pressure from a pipe 77 is admitted to the 55 space 78 beneath the piston head. The working pressure of the actuating fluid being equal throughout the system, the return stroke of the cylinder 70 that brings the rolls 2, 2 together will occur in a shorter time 60 than the out stroke that forces them apart, because the displacement at the top face of the piston head is less than that at its bottom or inner face. In practice, the ratio between the effective areas of the piston faces 65 is made one to eight, so that the return stroke of the cylinder is effected in approximately one eighth of the time required for its out or working stroke. As a result of this arrangement, therefore, the rolls 2—2 are slow- 70

130

ly and gradually shifted during the working stroke while their return is much more quickly accomplished, so as to avoid loss of time between successive operations. Obviously the time required for these movements may be readily varied by varying the relative rates of pumping that produce them.

The movements of the frame 33 together with its various appendages is brought about (in a manner similar to that described above in connection with the movement of the rolls 2-2) by movable cylinders 80-80 secured to the frame centrally between the upright guide columns 30-30 and 31-31. The pistons 81-81 of these cylinders are suspended centrally from the bridging pieces, 32-32 by means of tie-bolts 82-82 which extend through said bridging pieces and are threaded into bosses on the upper ends of the pistons. As in the case of cylinder 70, pressure is constantly maintained in the space 83 above the piston head 84 in each of said cylinders, through a port 85 and supply pipe 86. Downward movement of the frame 33 is effected by admitting the pressure fluid through pipe 87 to the spaces beneath the heads 84 of the pistons 81-81. The ratio of the areas of the oppositely acting piston surfaces is, in this instance, preferably made the same as in the case of the piston 71 of cylinder 70. Any leakage from the cylinders 70, 80, 80, is carried off by pipes 88 which telescope within branches 89 of a common connecting pipe 90 which leads to a discharge main 91, as best shown in Figs. I and III.

The pressure fluid is pumped to the cylinder 70 by means of a suitable force pump diagrammatically represented at 92 in Fig. I, and by a separate pump 93 of similar design to the cylinders 80-80. These pumps are, in the present instance, shown as associated with respective storage or collecting tanks 94 and 95 for the pressure medium, (preferably oil), thus adapting the pressure systems for closed circuit operation without waste of the medium. The pumps 92 and 93 are driven by a common vertical shaft, 96 whose lower end extends into a housing 97 (mounted on the base structure 12) and carries a mitre gear 98 that meshes with a similar gear 99 on the drive shaft 19 hereinbefore referred to. The pressure fluid supply pipes 86 for the upper ends of the cylinders 80 are connected to a pipe 100 which is supplied directly from the pump 93 by a main conduit 101. The other supply pipes 87 for these cylinders 80-80 are joined by a pipe 102 and connected to a conduit 103 extending from a controlling valve 104 which communicates with the pump 93 through a pipe 105. An exhaust connection 106 leads from the valve to the storage tank 95.

Pausing for a moment to refer to the detailed showing of the valve 104 in Fig. V, it

will be noted that in its lower position, as shown, the sliding piston 107 of the valve cuts off the supply of the pressure medium to the pipe 103, and connects the latter with the exhaust pipe 106; while in its upper position it permits direct communication between the pipes 105 and 103 to bring about the lowering of the frame, as already explained.

The valve 104 is operable manually to bring about the descent of the frame 33, by means of a hand lever 110 fulcrumed at 111 to said frame, see Fig. I. The motion of the lever is imparted to the valve stem through links 112 and 113 whose adjacent ends are coupled by a bell crank lever 114. Shifting of the valve to effect elevation of the frame at the end of the rolling operation is, however, accomplished automatically, under control of the separation of the support 1 and the rolls 2, 2, through the instrumentality of an adjustable stop screw 115 carried by the right hand roll carriage 40, (see Fig. III). As the roll carriage reaches the desired outermost limit of its movement, the stop 115 (see Fig. I) engages the projecting finger end 116 of a lever 117 pivoted to the frame 33 at 118 and connected to the link 112 at 119.

The constant pressure supply to the space 76 above the piston head in cylinder 70 is delivered to the pipe 74 from a main 120 connected to the pump 92. The supply pipe 77 of the cylinder 70 leads from a controlling valve 121, which is precisely of the same construction as the valve 104 already described. A pipe 122 serves to connect the valve 121 to the main 120 from the pump, and the discharge from the valve is returned to the storage reservoir 94 through a pipe 105 connection 123. The valve 121 is manually shiftable to bring about the outward (downward) or working stroke of the cylinder 70 by a hand lever 125, which is fulcrumed at 126 to the frame 33 and connected to the stem of the valve through an interposed link 127. The reverse shifting of the valve 121 to bring about the return stroke is effected automatically through a bell crank lever 128 pivoted on the frame 33, and having one of its arms in engagement with a projecting lug or stud on the link. During the raising of the frame 33, the other arm of the bell crank 128 is engaged by a pin 129 fixed to the upright or column 31 at the right of Fig. I, and projecting through an elongated vertical slot 130 in the guide sleeve 131 of said frame.

During the rolling operation, the blanks are held to the turn table 1, in the manner best illustrated in Fig. IV. Here the blank represented at "B" is shown in proper position upon the turn table with the stud 9 projecting through its central aperture to prevent displacement under the action of the 130

rolls. Rotation of the blank with respect to the turn table is prevented by a presser rod 132 whose axis coincides with that of the turn table 1 and which is carried by the frame 33, as clearly shown in the illustration. The lower end of the presser rod 132 is headed as indicated at 133, and also socketed to receive the stud 9 so that the blank may be securely held between said head and the top of the turn table. To the upper end of the rod 132 is secured a bearing cup 135 whose integral depending sleeve 136 is journalled for rotation in the hub of a cup-like fitting 137, removably secured to the frame 33 and affording clearance for axial movement of said bearing cup. The recess of the fitting 137 is closed at the top by a cap piece 138 having a hollow axial offset 139 for the reception and guidance of a vertically shiftable cylindrical shell 140 which is urged downward by a helical compression spring 141. A ball bearing 142 housed within the cup 135 serves to facilitate free rotation of the presser rod 132 with the turn table. When the frame 33 is raised with respect to the table 1, the extent of outward shifting of the rod 132 is limited by the engagement of the bottom of the bearing cup 135 with the floor of the recess in the fitting 137. The operation of the machine may be briefly described as follows:

The blanks B operated on are preferably circular in form, as illustrated in Figs. VI and VII, and initially of a size somewhat smaller in diameter than that desired for the finished blank; such blanks may readily be cut or stamped from stock of uniform thickness. Preparatory to being rolled, each blank B may be preheated to facilitate the flow of the metal during the rolling operation. The frame 33 being raised to the full extent determined by the engagement with the stop collars 38 upon the columns 30, 31, the rolls 2, 2, (in their innermost position, as shown in the illustration) are thereby sufficiently raised to permit the easy placing of the blank B over the stud 9 upon the turn table 1. After the blank has been placed upon the turn table, the hand lever 110 is pulled outward to the position shown in Fig. I, thereby shifting the piston of the valve 104 upward and admitting pressure fluid to the space beneath the heads 84 of the pistons 81. This causes the cylinders 80, 80 to be forced downward so as to move the frame 33 and its appendages toward the table 1 as far as permitted by the limiting stop collars 36 on the columns 30, 31. In the course of the downward movement of the frame 33, the socketed end of the presser rod 132 automatically slips over the stud 9 and holds the blank B securely against rotation on the die face 4 in the top of the plate 3 of the turn table. During this downward movement of the frame 33, the spring 141 yields sufficient-

ly to insure adequate pressure of the rod 132 on the blank B by the time the rolls 2, 2 bear firmly on the blank. As soon as the rolls 2, 2 are brought into contact with the blank, they begin to rotate by friction therewith, owing to the rotation of the turn table.

After the frame 33 has thus been lowered to the full extent, the operator pulls the hand lever 125 to the position shown in Fig. I, thereby shifting the piston of the valve 121 to admit pressure fluid through the pipe 77 to the space beneath the piston head in the cylinder 70, thus overcoming the constant pressure above, and causing gradual downward movement of said cylinder. This motion is transmitted through the rockers 65, 65, to the carriages 40, 40. As a consequence, the rolls 2, 2 are uniformly and progressively shifted in radially opposite directions across the face of the rotating blank at a slight inclination relatively to the support 3, so as to produce a variation in thickness of the forged product. In the present instance, this inclination of relative movement and the resultant attenuation of the disk are due to the concavity of the upper surface of the element 3, as indicated in Fig. VIII. The result of this action is shown in Fig. VIII where it will be seen that the metal of the blank is displaced and worked outward by the cooperation of the inclined die surface of the plate 3 with the rolls 2, and "flows" toward the periphery of the blank. The peripheral curl or flare resulting from the natural dishing of the blank under the pressure of the rolls 2, 2 is held in check by the bevel faces of the latter so as to avoid the formation of a sharp angle such as might result in fracture of the metal under the strain. These faces also have a metal spinning action on the peripheral flare which draws the metal of such flaring flange and causes it to flow radially of the blank. The operation proceeds in this manner until the blank has been completely rolled into a disk of tapered cross sectional configuration, as represented in Fig. IX. It will be apparent that on account of the comparatively narrow tread of the rolls 2, 2, the metal of the blank is very gradually displaced, and that under the characteristic operation of the machine this displacement is distributed uniformly in all radial directions so as to obviate any tendency of the blank to buckle or fracture. As a result, the finished disk becomes somewhat larger than the original blank,—this difference being indicated by comparison of Figs. VII and IX.

After the rolls have been separated to the extent necessary to effect the formation of the disk, the stop screw 115 on the right hand roll carriage 140 (Fig. I) engages finger 116 of the arm 117. This causes the reverse shifting of the piston of the valve 104 thereby breaking the communication between

pipes 105 and 103 and opening the latter to the exhaust pipe 106 to permit discharge from the space beneath the pistons 81 of the cylinders 80. The constant pressure in the space 83 above the heads 84 of the pistons 81 thereupon becomes effective to raise the cylinders 80, together with the frame 33, to which they are attached, and separate the support 1 and the rolls 2, 2. As the frame 10 nears the end of its upward movement, the fixed pin 129 on the column 31 on the right of Fig. I engages the bell crank 128, thereby causing the reverse shifting of the piston of valve 121, and the exhaust of the pressure 15 fluid from beneath the larger head of the piston 71 of the vertically acting hydraulic cylinder 70. This release allows the constant pressure on the smaller head of said piston to become effective and raise the cylinder 70, 20 which causes the return or bringing together of the rolls 2, 2, to the initial or starting position. Thereupon the machine is again in readiness for the next operation. The return strokes of the cylinders 70 and 80, 80 are 25 accomplished in a comparatively short interval, so as to avoid loss of time between successive operations of the machine. The machine is therefore, semi-automatic in operation, requiring attention only when the 30 process is initiated and automatically returning to starting condition after its completion each time.

In view of the arrangement of the levers 110 and 125 in close proximity to each other, 35 the operator may, if desired, operate both levers simultaneously, thereby initiating a complete automatic cycle which will be carried out with further attention on his part.

This machine is useful for the rolling of 40 tapered disks, or disks of varying cross section, from a sheet metal blank of uniform thickness. The cross section of the rolled disk will be determined by the contour given 45 by the die face of the plate 3, on which the blank is supported. This machine may also be used for rolling tapered disks or disks of varying cross section for the purpose of causing a metal flow to improve the surface 50 of the disk. I have found that, if disks which have been previously tapered by other methods are rolled cold in my machine, the resulting flow of metal produces a surface 55 which is very well adapted for receiving paint or enamel. In the machine illustrated in this application, the rolls are fed radially of the blank until the periphery of the blank 60 is reached but the rolls may be stopped and the roll frame lifted before the rolls reach the periphery of the blank, thus leaving a peripheral flange on the disk which has not been reduced in thickness. This is desirable in some instances.

The machine illustrated in the accompanying 65 specification and covered by the claims hereof is an improvement on the ap-

paratus described and claimed in my co-pending application for process of and apparatus for rolling metallic disks, Serial No. 408,231, filed September 4, 1920, and the process described and claimed in said application may be carried out by the machine disclosed herein.

I am aware that the particular machine illustrated and described in this specification is capable of considerable modification and 70 variation without departing from the spirit of my invention and, therefore, I claim my invention broadly, as indicated by the appended claims.

Having thus described my invention I 80 claim:

1. A machine of the class described comprising a support for the blank to be rolled and a roll frame relatively movable toward or away from one another; a roll on said 85 frame for cooperating with the said support movable crosswise of the blank during the rolling operation; and hydraulic means for relatively moving said frame and said support as aforesaid, and for moving said roll as aforesaid.

2. A machine of the class described comprising a support for the blank to be rolled and a roll frame relatively movable toward or away from one another; a roll on said 95 frame for cooperating with the said support movable crosswise of the blank during the rolling operation; and differential means for relatively moving said frame and said support as aforesaid, and for moving said roll 100 as aforesaid.

3. A machine of the class described comprising a support for the blank to be rolled and a roll frame relatively movable toward or away from one another; a roll on said 105 frame for cooperating with the said support movable crosswise of the blank during the rolling operation; hydraulic means for moving said frame toward said support; and hydraulic means on said frame for moving 110 said roll as aforesaid.

4. A machine of the class described comprising a support for the blank to be rolled and a roll frame relatively movable toward or away from one another; a roll on said 115 frame for cooperating with the said support movable crosswise of the blank during the rolling operation; and means including a vertically acting hydraulic cylinder for moving said roll as aforesaid.

5. A machine of the class described comprising a support for the blank to be rolled and a cooperating roll; hydraulic means for maintaining a working pressure between 120 said roll and said support; and means for progressively shifting said roll crosswise of said support during the rolling operation at an inclination relatively to the support to produce a variation in thickness of the 125 product.

6. A machine of the class described comprising a support for the blank to be rolled and a cooperating roll; means for maintaining a working pressure between said roll and said support; and hydraulic means for progressively shifting said roll crosswise of said support during the rolling operation.
7. A machine of the class described comprising a support for the blank to be rolled; 10 a roll cooperating with said support; a hydraulic cylinder for maintaining the working pressure between said roll and support during the rolling operation; and means for automatically releasing pressure fluid from 15 said cylinder after the completion of the operation to permit removal of the rolled blank.
8. A machine of the class described comprising a support for the blank to be rolled; 20 a shiftable roll cooperating with said support; a hydraulic cylinder for applying pressure between said roll and the support during the rolling operation; and controlling means associated with said cylinder automatically actuated by the roll at the completion of the rolling operation to release 25 the pressure fluid from the cylinder and permit removal of the rolled blank.
9. A machine of the class described comprising a support for the blank to be rolled; 30 a cooperating roll adapted to be moved crosswise of the support in contact with the blank; means for maintaining a working pressure between the roll and the support during the rolling operation; and means for automatically separating said roll and support and restoring the same to starting position after the completion of each rolling operation.
- 40 10. A machine of the class described comprising a support for the blank to be rolled; a cooperating roll, and means for slowly shifting the roll crosswise of the support while in contact with the supported blank 45 to roll the latter, and for quickly returning the roll automatically to its initial or starting position after the rolling operation.
11. A machine of the class described comprising a support for the blank to be rolled; 50 a cooperating roll; and a differential hydraulic cylinder for slowly shifting the roll crosswise of the blank while in contact with the same during the rolling operation, and for quickly returning the roll to its initial 55 or starting position after the rolling operation.
12. A machine of the class described comprising a support for the blank to be rolled; a cooperating roll; means for moving the 60 roll into contact with the blank and so maintaining the same; means for shifting the roll crosswise of the blank during the rolling operation; and means for automatically causing the raising of the roll from the blank after the completion of the rolling 65
- operation and the return of the roll to initial or starting position after having been raised.
13. A machine of the class described comprising a support for the blank to be rolled; 70 a cooperating roll; a double acting hydraulic cylinder for moving the roll bodily with respect to said support; a second double acting hydraulic cylinder for shifting the roll in a direction crosswise of the support; separate controlling valves for the said cylinders; means whereby said valves may be manually operated to bring about the relative movement of the support and roll to active positions; and means for automatically operating said valves successively so as to first cause the retraction of the roll with respect to the support, and then the restoration of the roll to its initial or starting position, after the completion of the rolling 85 operation.
14. A machine of the class described comprising a support for the blank to be rolled; a cooperating roll; a double acting hydraulic roll for moving the cylinder bodily toward or away from said support; a second double acting hydraulic cylinder for shifting the roll in a direction crosswise of the support; a separate controlling valve associated with each cylinder; means for causing the actuation of the valve associated with the first mentioned cylinder to bring about the retraction of the roll when the latter has reached the end of its active movement, and means for actuating the valve associated with the second mentioned hydraulic cylinder to bring about the restoration of the roll to its initial or starting position.
15. In a machine of the class described, 90 the combination of a support for the blank to be rolled and a cooperating roll; a frame with ways for movement of said roll crosswise of the support to roll a blank thereon, said support and said frame being vertically movable toward and away from one another for rolling and to permit removal of the rolled blank; and means for shifting said roll crosswise of the support on said ways comprising a vertically acting hydraulic cylinder on said frame.
16. In a machine of the class described, 95 the combination of a support for the blank to be rolled and a cooperating roll bodily rotatable relative to one another and movable toward and away from one another for rolling and to permit removal of the rolled blank; means for centering the blank with reference to said support and said roll; and means controlled by relative movement of said support and said roll toward and away from one another for holding the work on said support against rotation.
17. A machine of the class described comprising a support for the blank to be rolled 100

and a roll carrying frame relatively movable toward and away from each other; a pair of rolls carried by the frame, one located at each side of the center of the blank; 5 means for imparting relative movement to the frame and support and for urging them together under pressure; and a fluid pressure means for moving the rolls oppositely and radially of the blank in a progressive 10 manner while operating on the same to continually effect changes of form therein.

18. A machine of the class described comprising a rotating support for the blank, a roll carrier movable toward and from 15 said support, rolls carried by said carrier and cooperating with the blank, means for moving said carrier toward the support to apply the rolls to the blank under pressure, and means for moving the rolls radially of 20 the blank.

19. A machine of the class described comprising a rotating support for the blank, a roll cooperating with said support, means for approaching said roll and the support to 25 apply pressure to the blank, means for moving the roll radially of the blank, and means for automatically separating the roll and the blank when the roll reaches a predetermined point in its radial movement.

30. 20. A machine of the class described comprising a rotating support for the blank, a roll cooperating with said support, means for moving said roll toward the support to apply it to the blank under pressure, means 35 for moving the roll radially of the blank, and automatic means for moving the roll away from the blank and returning it radially to starting position to permit a change of blanks on the support.

40. 21. The method of rolling tapered disks comprising clamping a heated circular blank of metal on the dished or formed surface of a rotating platen, then forcibly projecting against the free surface of said blank near 45 the central portions thereof one or more narrow faced curved edge rolls, then traversing said rolls over said blank to or toward the periphery thereof, the traverse of said rolls being in a plane at substantially right angles to the axis of the rotation of said platen.

50. 22. The method of rolling a disk which consists in heating a blank, clamping the same securely on a rotating platen, and traversing the blank outwardly from the center by a pair of rolls forcibly engaging the blank, thereby expanding or shaping it as desired.

55. 23. The method of rolling a disk which comprises heating a blank, firmly clamping the central portion thereof on a rotating platen shaped to conform to the desired section of the disk, bringing the rotating blank into contact with a pair of rolls having their 60 axes in alignment and on opposite sides of

the axis of the platen, and retracting the rolls outwardly from the center of the blank, thereby causing the rolls to traverse the blank so as to expand and shape it as desired.

70

24. A disk rolling machine comprising a rotatable platen, the exposed surface of which is dished or formed to the shape of one side of a finished disk, centrally located clamping means associated therewith, one 75 or more narrow faced rolls with their peripheries adjacent said platen, means for projecting said rolls toward and from said platen, and for traversing same toward and from the periphery thereof.

80

25. A disk rolling machine comprising a rotatable platen, means for centrally clamping a blank thereon, one or more rolls provided with means for projecting them forcibly against and for traversing them over 85 said blank, whereby said blank is rolled to greater diameter.

26. A disk rolling machine comprising a rotatable platen, means for centrally clamping a blank thereon, one or more narrow 90 faced rolls provided with means for projecting them forcibly against and for traversing them over said blank, whereby the blank is rolled to a greater diameter.

27. A disk rolling machine comprising a 95 rotatable platen, means for centrally clamping a blank thereon, one or more narrow faced curved edge rolls provided with means for projecting them forcibly against and for traversing them over said blank, whereby 100 the blank is rolled to a greater diameter.

28. A disk rolling machine comprising a rotatable platen, having a dished or tapered working surface, means for centrally clamping a blank thereon, one or more rolls provided with means for projecting them forcibly against and for traversing them over 105 said blank, whereby said blank is rolled to a greater diameter.

29. A disk rolling machine comprising a 110 rotatable platen, means for centrally clamping a blank thereon, one or more narrow faced curved edge rolls provided with means for projecting them forcibly against and for traversing them over said blank, whereby 115 the blank is curled away from said platen.

30. A disk rolling machine comprising a rotatable platen, having a dished or tapered working surface, means for centrally clamping a blank thereon, one or more rolls provided with means for projecting them forcibly against and for traversing them over 120 said blank, whereby said blank is rolled to a greater diameter and tapered.

31. In a machine of the class described, 125 the combination of a support for the blank to be rolled and a cooperating roll bodily rotatable relative to one another and bodily movable toward and away from one another for rolling and to permit the removal of 130

- the rolled blank, means for centering the blank with reference to said support and said roll, and yielding means controlled by relative movement of said support and said roll toward and away from one another for holding the work on said support against relative rotation. 60
32. In a machine of the class described, the combination of a support for the blank 10 to be rolled and a co-operating roll bodily rotatable relative to one another and bodily movable toward and away from one another for rolling and to permit the removal of the rolled blank, means for centering the blank 15 with reference to said support and said roll, and rotatable clamping means for holding the work on the support against relative rotation which means is controlled in both its clamping and rotation by the relative 20 movement of said support and said roll toward and from one another. 25
33. A machine of the character described, a rotatable platen to support the blank disposed in a horizontal plane, and a relatively movable overhead roll support, guide-ways on the under side of said support symmetrically disposed on opposite sides of the platen axis and a roll or rolls supported slidably on said guide-ways. 30
34. A machine of the class described comprising a support for a blank to be rolled and a roll frame relatively movable toward and away from one another, a roll on said frame for cooperating with said support 35 movable substantially radially of the blank during the rolling operation, and a prime mover carried by said roll frame for so moving said roll relative to the blank. 40
35. A machine of the class described comprising a support for a blank to be rolled and a roll frame relatively movable toward and away from one another, a roll on said frame for cooperating with said support 45 movable substantially radially of the blank during the rolling operation, a plurality of columns for supporting said frame, and a prime mover also supported by said columns for relatively moving said frame and support as aforesaid. 50
36. A machine of the class described comprising a rotatable support for a blank to be rolled, a roll frame relatively movable toward and away from the support, a pair of roll carriages slidably mounted on said frame so as to move transversely of the direction of the relative movement of said frame and said support, a pair of bell crank levers, one pivoted to each of said carriages, and means for simultaneously operating said levers, as and for the purpose specified. 60
37. A machine of the class described comprising a rotating table adapted to support a blank to be rolled, a frame relatively vertically movable with respect to said table, a roll carried by said frame and adapted to operate on a blank supported on said table, and mechanism carried by said frame for causing said relative vertical movement of frame and table and for relatively moving the roll and table radially of the blank 65 supported by the table. 70
38. A machine of the class described comprising a support for the blank to be rolled and a cooperating roll, means for causing a relative movement between the support and the roll to bring the roll into contact with the blank and so maintaining the same, means for relatively shifting the roll and support to cause the roll to radially traverse the blank and means for automatically returning the roll to the starting position after the roll has reached a predetermined point in its traversing movement. 75
39. A machine of the class described comprising a support for a blank to be rolled 80 and a cooperating roll, means for causing a relative movement between the support and the roll to bring the roll into contact with the blank, means for relatively radially traversing the roll with respect to the support 85 while in rolling engagement with the blank, means for separating the roll and the blank, means for retraversing the roll to the starting position to complete the cycle of movements and manually controllable means for 90 instituting the complete cycle of movements. 95
40. A machine of the class described comprising a support for a blank to be rolled and a cooperating roll, means for causing a relative movement between the roll and 100 the support to bring the roll into contact with the blank, means for relatively moving the roll and the support to cause the roll to radially traverse the blank, means for separating the roll and the support, means 105 for retraversing the roll to the starting point, said means being interlocked so that the movements causing the radial traverse of the roll initiates the separation movement and the separation movement initiates the 110 retraverse movement.

In testimony whereof, I have hereunto signed my name at Philadelphia, Pennsylvania, this first day of October, 1920.

JOHN W. SMITH.
